Primary Examiner — Sandra Snapp*Assistant Examiner* — Mehri Bajoul*(74) Attorney, Agent, or Firm* — Gearhart Law LLC(57) **CLAIM**

The ornamental design for a pet carrier, as shown and described.

DESCRIPTION

FIG. 1 is a perspective view of the pet carrier.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof; and,

FIG. 8 is a perspective view of the pet carrier in an alternate position.

The broken lines showing stitches depict portions of the pet carrier that form part of the claimed design. The shoulder strap is shown with symbolic breaks in its length. The appearance of any portion of the article between the break lines forms no part of the claimed design.

1 Claim, 7 Drawing Sheets(56)
